James Hamilton

UNITED STATES PATENT OFFICE.

ALFRED AUGER, OF MANCHESTER, NEW HAMPSHIRE.

PLATE-LIFTER.

N . 916,524.

Specification of Letters Patent. Patented March 30, 1909.

Application filed September 1, 1908. Serial No. 451,170.

To all whom it may concern:

Be it known that I, ALFRED AUGER, a citizen of the United States, residing at Manchester, in the county of Hillsboro and State of New Hampshire, have invented certain new and useful Improvements in Plate-Lifters, of which the following is a specification, reference being had to the accompanying drawings.

10 My invention relates to improvements in plate-lifters; and an object of my invention is to provide a plate-lifter which will be simple in construction, comparatively cheap in manufacture and efficient in use.

15 In the drawings illustrating the principle of my invention and the best mode now known to me of applying that principle, Figure 1 is a perspective view of my new plate-lifter; Fig. 2 is a plan of the same; 20 Fig. 3 is a side elevation; and Fig. 4 is a section on the line A—A of Fig. 1.

The wooden handle-bar *a* is formed at one end with a handle *b* and in each of its sides with a slot *c*. The front holding-portion or 25 stationary holder is formed of a single piece of wire, the middle of which extends transversely beneath the handle-bar at the front end of the latter and is held in place by a suitable staple *d*. The wire is then bent upwardly and inwardly on each side and enters the slots *c*. The two branches of the wire then extend forwardly in the slots *c* to the front end of the handle-bar *a*, where they diverge from each other, as is shown at *e* in 30 Figs. 1 and 2. The two branches of the wire are next bent downwardly to form the legs *f* and then rearwardly to form the toes *g*, which are adapted to lie under the rim of the plate *h* and support the latter. At the front 35 end of the handle-bar *a* is provided a wire loop or collar *i*, which serves to hold the branches *e* of the front holding-portion in place in the slots *c*. The rear holding-portion or 40 slideable holder is also made of a single piece of wire, the middle portion *j* of which lies above the handle-bar *a* and is then bent downwardly and inwardly and enters the slots *c* formed one on each side of the handle-bar *a*. The two branches of the wire ex- 45 tend in the slots *c* forwardly for a distance, and are then bent outwardly and downwardly to form legs *f'* the extremities of which are bent forwardly to form toes *g'*. The latter serve the same purpose as the 50 toes *g* of the front or stationary holder.

One end of a coil-spring *k* is fastened to

the top of the handle-bar *a*, while its other end is fastened to one end of a pull-wire *m*, the other end of which is formed with a finger-loop *n*. The end of the pull-wire *m* 60 which is made fast to the coil-spring *k* is also fastened to the rear or slideable holder, at its mid-portion *j*. The pull-wire *m* extends through the guide-eye *o* mounted on the top of the handle-bar *a*. 65

I claim:

1. A plate-lifter consisting of the combination of a handle-bar formed with a slot in each of its sides; a stationary holder made from one piece of wire the mid-portion of 70 which extends across and is fastened to said handle-bar near its front end; the branches of said wire extending forwardly in said slots to the front end of said handle-bar and then diverging outwardly, each of said branches 75 being next bent downwardly to form a leg and then rearwardly to form a toe for engagement with the rim of the plate; a slideable holder made from one piece of wire the mid-portion of which extends across said 80 handle-bar and the ends of which extend forwardly one on each side of said handle-bar in one of said slots, each of said ends being further bent first downwardly to form a leg and then forwardly to form a toe for engagement with the rim of the plate; a pull-wire 85 one end of which is fastened to said slideable holder; and a coil-spring one end of which is fastened to said handle-bar and the other end of which is fastened to said pull-wire. 90

2. A plate-lifter consisting of the combination of a handle-bar formed with a slot in each of its sides; a stationary holder made from one piece of wire the mid-portion of which extends across and is fastened to said 95 handle-bar near its front end; said wire being bent inwardly to enter said slots on each side of said handle-bar; the two branches of said wire then diverging outwardly and each being bent first downwardly to form a leg and 100 then rearwardly to form a toe for engagement with the rim of the plate; a collar which encircles the two branches of said stationary holder at the front end of said handle-bar to hold said branches in said slots; a slideable 105 holder made from one piece of wire the mid-portion of which extends across said handle-bar and the ends of which extend forwardly one on each side of said handle-bar in one of said slots, each of said ends being bent outwardly from its slot, next downwardly to form a leg and then forwardly to form a toe 110

for engagement with the rim of the plate; a
pull-wire one end of which is fastened to the
mid-portion of said slideable holder; and a
coil-spring one end of which is fastened to
5 said handle-bar and the other end of which is
fastened to said pull-wire.

In testimony whereof I have hereunto set

my hand, this 27th day of August, A. D.,
1908, in the presence of the two undersigned
witnesses.

ALFRED AUGER.
